APPARATUS FOR THE MANUFACTURE OF
TAPERED CONDUCTORS

Gordon F. Laing, Delavan, Wis., assignor to The
George W. Borg Corporation, Chicago, Ill., a
corporation of Delaware

Application March 29, 1945, Serial No. 585,475

3 Claims. (Cl. 204—206)

1

The present invention relates in general to methods and apparatus for the manufacture of tapered conductors, such as are suitable for use in the manufacture of non-linear rheostats and potentiometers, and the object of the invention is to provide new and improved methods and apparatus of this character.

The invention may be considered as an improvement on the invention disclosed in the pending application of Thomas B. Gibbs et al., Serial No. 525,764, filed March 9, 1944 (now Patent 2,605,218) which discloses a method and apparatus for making tapered conductors from conductors or wires of uniform cross-section by drawing such wires through an electrolytic bath in which they are subjected to anodic reduction. The taper is produced by progressively decreasing the speed at which the wires are drawn through the bath, thereby progressively increasing the time in the bath and the amount of metal removed from the wires.

A feature of the present invention is the use of alternating current in the electrolytic bath rather than direct current, which makes possible a more compact and efficient arrangement of the electrolytic cell system.

A further feature of the invention is the use of alternating current of relatively high frequency, on the order of 1000 cycles per second, or higher, which reduces the evolution of gas in the electrolytic cells and increases the rate of anodic reduction.

The foregoing and other features will be described more in detail hereinafter with reference to the accompanying drawings, in which—

Fig. 1 is a plan view of the electrolytic cell system showing also the tank and the circulating system for the electrolyte;

Fig. 2 is a section on the line 2—2, Fig. 1;

Fig. 3 is a section on the line 3—3, Fig. 1; and

Fig. 4 is a diagrammatic circuit drawing of the complete apparatus.

Referring to the drawings, the reference character 10 indicates part of a table, bench or other support on which the apparatus is mounted. The support 10 has a rectangular opening therein for receiving a tank which comprises the relatively shallow portion 11 and the well 12. The tank has a marginal flange 13 all around which rests on the support 10, as shown in Figs. 2 and 3. The tank should be made of suitable acid-proof material or should have a lining of acid-proof material.

The tank is divided into two sections, I and II, Fig. 3, by an impervious and non-conducting partition 19.

Two bars 14 and 15 are provided for supporting the electrolytic cells above the tank. At one end the bars rest on the flange 13 of the tank and at the other end they rest on the cross bar

2

16 which is secured to the sides of the tank, as indicated in Fig. 1. These bars may be made of suitable acid-proof material such as polystyrene.

There must be at least two electrolytic cells, and for efficient operation there should be a considerable number of them. The drawings show fourteen cells, indicated by reference characters 21 to 34, inclusive. These cells and the two headers 17 and 18 are preferably made from strips of polystyrene secured together by means of a cement made by dissolving polystyrene in a suitable organic solvent.

The electrolytic cell 22 comprises a bottom strip 37, which rests on the bars 14 and 15, the side strips 35 and 36, and the short end strip 38. These strips are cemented together as previously mentioned and form a relatively long and narrow cell which is open at one end and is closed at the other end by the end strip 38. The side walls 35 and 36 have slots as indicated at 44, Fig. 3, and there is a partition 39 near the closed end of the cell. This partition is lower than the cell walls but is somewhat higher than the bottoms of the slots 44. Between the partition 39 and the end wall 38 there is an opening 41 leading to the pipe or tube 42 which is cemented to the bottom strip 37.

The reference character 40 indicates an electrode, which is preferably a strip of platinum resting on the bottom of the cell. At the left hand end the electrode is held down by the partition 39, as shown in Fig. 3, and at the right hand end it is bent down around the end of the bottom strip 37.

The cells 23 to 33, inclusive, are the same as the cell 22 which has been described. The two end cells 21 and 34 are the same also, except that the side walls 45 and 48 are made somewhat longer so as to form the end walls of the headers 17 and 18.

The cells are arranged on the bars 14 and 15 as shown in Fig. 1, with the odd numbered cells 21, 23, etc. having their open ends at one side of the assembly while the even numbered cells 22, 24, etc. have their open ends on the other side. The cells are spaced apart by the end walls such as 38, which should be cemented to the side walls of the adjacent cells after they have been properly lined up. In this way the cells are firmly secured together.

The header 17 has the bottom strip 47 and the side wall strip 46 and the ends are closed by the extended side walls 45 and 48 of the cells 34 and 21. The bottom strip has shallow notches at the points where the electrodes such as 40 leave the associated cells, to avoid leaving a space between the edge of the strip and the ends of the cells. The parts being well cemented together a header is formed which spans the row of cells 60 and opens into the even numbered cells.

The header 18 includes the bottom strip 49 and the side strip or wall 50 and is similar to header 17. The header 18, however, opens into the odd numbered cells.

After the cells and headers are assembled as described the joints may be painted with the polystyrene cement to insure that no leaks are present.

The electrodes such as 40 which are associated with the even numbered cells are all connected to the bus bar 52, while the electrodes associated with the odd numbered cells are connected to the bus bar 51.

There are two separate and independent electrolyte circulating systems, which supply electrolyte to the headers 17 and 18 respectively. One of these circulating systems includes the motor 54 and the pump 53. These parts are of known construction and need not be described in detail. The pump 53 is located in the well 12, section II, and delivers electrolyte from section II of the tank to the vertical pipe 55, whence it flows to the header 18 by way of the horizontal pipe 56, the hose 57, the elbow 58, and the channeled block 60, which is cemented to the bottom wall 49 of the header. The other circulating system includes the motor 54' and a pump similar to pump 53. The pump associated with motor 54' is located in the well 12, section I, and delivers electrolyte from section I of the tank to the vertical pipe 61, whence it flows to the header 17 through horizontal pipe 62, hose 63, elbow 58', and the channeled block 60'.

The volume of electrolyte delivered to the headers is controlled by means of the valves 64 and 67. The stem of valve 64 is threaded into a rectangular plate 66 which is supported on the side wall 46 of header 17 and on the cells 26-29. The valve stem may be rotated in one direction or the other by means of a screw driver to raise or lower the V-shaped valve head and thus regulate the effective area of the opening in the bottom 47 of the header through which the electrolyte flows from the channel in the block 60'. A locknut 65 is provided by means of which the valve can be secured in adjusted position. The valve 67 is similar to valve 64 and regulates the flow of electrolyte into the header 18.

The composition of the electrolyte may vary somewhat depending on the kind of wire to be processed. For the manufacture of tapered conductors from Nichrome or similar resistance wire a mixture of ortho-phosphoric acid and sulphuric acid has been found to give good results. The composition, for example, may be as follows:

	Parts
H ₃ PO ₄	300
H ₂ SO ₄	60
H ₂ O	60

In the above formula, the proportions given are by volume. The sulphuric acid is concentrated, while the phosphoric acid is 85% concentrated, that is, it contains 15% of water.

The temperature of the electrolyte should be maintained constant at a fairly high value, 50 degrees C., for example. Although not shown in the drawings, it will be understood that suitable heating and temperature control apparatus will be provided. Apparatus such as disclosed in the Gibbs et al. application previously referred to may be used.

The cell 69 is a washing cell and is supplied with water through a suitable hose connection 68. The water fills the cell 69 to the level of

the end wall 77 over which it overflows into the outer cell 78 which is drained by the hose 79. The walls of the cells 69 and 78 are slotted like the walls of the electrolytic cells 21, 22, etc.

The first four electrolytic cells 21 to 24 are shown diagrammatically in Fig. 4, with the bus bars 51 and 52. These bus bars are connected to the secondary winding of the constant current transformer 70 by means of the conductors 73 and 74. An ammeter 71 is included in the circuit. The primary winding of the transformer 70 is connected to the single phase A. C. generator 75 by way of the auto-transformer 72. The generator 75 is driven by the motor 76 which is supplied with commercial current through the switch S1.

The motor generator set 76-75 is employed in order to convert the commercial alternating current having a frequency of 60 cycles per second into alternating current of higher frequency, 3000 cycles per second, for example. Other arrangements for supplying high frequency alternating current could be used.

The wires 81, 82, 83 and 84 from which tapered conductors are to be made are carried on the spools 85, 86, 87 and 88, respectively, which are supported for rotation in any suitable manner. Braking devices (not shown) may be provided to prevent free rotation of the spools.

The wires 81-84 are drawn through the electrolytic cells by winding them on the four take-up spools 89-92. These spools are clamped against the flange 93 on shaft 94 by means of the wing nut 95.

Two notched guide rods are indicated at 96 and 97. It will be understood that in practice the spools 85-88 are located at least several feet away from the guide rod 96, so that there will be no danger of the wires slipping out of the notches in the guide rod as they unwind from the spools. The same is true as regards the relation between the spools 89-92 and the guide rod 97, although the spacing here is desirable mainly in order to afford the necessary room for a suitable device (not shown) for causing each wire to be wound up on its associated spool in a single evenly applied layer.

The shaft 94 is driven by the motor 98 through the medium of a variable speed mechanism 99. A variable speed mechanism such as is disclosed in the Gibbs et al. application previously referred to may be used. Another variable speed mechanism which is suitable for the purpose is disclosed in the application of Gordon F. Laing, Serial No. 547,041, filed July 28, 1944 (now Patent 2,422,306).

The operation of the apparatus in the manufacture of tapered conductors may now be explained, it being assumed for this purpose that the apparatus is installed and connected up as shown diagrammatically in Fig. 4.

The well 12 of the tank having been filled with electrolyte, the switch S3 may be closed to start the motors 54 and 54' which drive the pump 53 and the corresponding pump in the other section of the tank. The operation of the pumps transfers electrolyte from the well to the headers 17 and 18 from which it flows into the electrolytic cells, header 17 supplying electrolyte to the even numbered cells 22, 24, etc. and header 18 supplying electrolyte to the odd numbered cells 21, 23, etc.

Considering cell 22, for example, the electrolyte flows from header 17 through the open end of the cell and fills the cell to the top of the parti-

tion 39. As the electrolyte continues to enter the cell it begins to overflow over the partition and is returned to the tank by way of the drainage opening 41 and the tube 42. Thus a definite current of electrolyte is established, flowing lengthwise of the cell.

The action at the other cells is the same as described, the electrolyte entering each cell at its open end, overflowing the partition at the opposite end, and draining back to the tank by way of the associated drainage opening. The valves 64 and 67 should be adjusted to supply an adequate volume of electrolyte to the headers 17 and 18, sufficient to maintain a vigorous flow through the cells. In this connection it will be understood that the pumps have some excess capacity and that the valves are adjusted to limit the volume of electrolyte delivered to the headers to the desired value.

It will be noted that the drainage tube 42 for cell 22 and the tubes which drain the other even numbered cells all empty into section I of the tank, from which electrolyte is pumped to the header 17 to supply these even numbered cells. The drainage tubes from the odd numbered cells, on the other hand, empty into section II of the tank, from which electrolyte is pumped to header 18 for the odd numbered cells. The odd and even numbered cells are thus supplied by separate circulating systems which are electrically insulated from each other by the partition 19 in the tank.

The wash water may now be turned on and enters the washing cell 69 by way of the hose connection 68, filling the cell and overflowing over the end wall 77 of the washing cell into the outer cell 78; whence it is drained off through the hose connection 79.

Due to the slots 44 in the walls of the electrolytic cells, a certain amount of leakage occurs. The electrolyte which leaks through the slots runs down the outside of the cell walls, which are spaced apart far enough for this action to take place, and drips into the tank. There is also a leakage of water through the slots in the walls of the washing cell 69. The leakage water collects in the outer cell 78 in which the water level is lower than the bottoms of the slots due to the location of the drainage opening near the bottom. Accordingly, there is no leakage through the slots in the walls of cell 78.

It may be assumed now that the four spools of wire 85-88 have been placed on their supports as indicated and that the four take-up spools 89-92 have been assembled on shaft 94. The wires 81-84 are pulled off from their respective spools one at a time and are passed under the guide rod 96, over the electrolytic cell system, under the guide rod 97, and are finally attached to the take-up spools, notches being provided in the flanges of the take-up spools for this purpose. The wires are then adjusted in the notches of the guide rods and in the slots of the electrolytic cells and washer cells and the spools 85-88 are rotated backwards if necessary until the wires become taut. It will be understood that the lower sides of the guide rods 96 and 97 should be at the same level or slightly lower than the bottoms of the slots in the cell walls so that as the wires are drawn through there will be no tendency for them to rise in the cells.

The operator may now close the switch S1 to start the motor generator set 76-75. The generator 75, having attained its running speed, delivers alternating current to the primary winding of the transformer 70, the secondary winding of

which delivers alternating current to the electrolytic cell system. The amount of current flowing in the secondary circuit is indicated by the ammeter 71 and it may be assumed that the auto-transformer 72 has been adjusted so that the current has the proper value. The current should be as high as possible consistent with the carrying capacity of the wires. In the manufacture of tapered conductors having a larger diameter of about 10 about 5 to 8 mils and a smaller diameter of about 1 mil or more with the apparatus described about 3 amperes per wire may be used. The high current value is desirable in order to give the tapered wires a smooth surface.

15 The anodic reduction of the wires takes place in the odd and even numbered cells alternately. During the half cycles in which the bus bar 51 is positive, current flows over a circuit which may be traced from bus bar 52, platinum electrodes in 20 the even numbered cells, electrolyte in the even numbered cells, wires 81-84, electrolyte in the odd numbered cells, platinum electrodes in the odd numbered cells, and the bus bar 51, and anodic reduction takes place in the even numbered cells, where the wires are positive with respect to the electrodes. During the intervening half cycles the circuit is the same but the direction of current flow is reversed and anodic reduction of the wires takes place in the odd 25 numbered cells.

30 The evolution of gas is less than in an apparatus using direct current. The gases produced in each type of apparatus are hydrogen and oxygen. Both hydrogen and oxygen are 35 produced by electrolysis of the water in the electrolyte. The gases are liberated as atomic hydrogen H and atomic oxygen O and can combine to form water H_2O if given an opportunity to do so, being otherwise separately converted 40 to molecular hydrogen H_2 and molecular oxygen O_2 which are given off as bubbles of gas.

The reduction in gassing in the present apparatus, using alternating current is believed to 45 be due to the fact that with this type of apparatus the gases have a greater opportunity to combine to form water. In the direct current apparatus the hydrogen and oxygen produced by electrolysis are liberated at different electrodes, hydrogen being liberated at the cathode and oxygen at the anode (the wires), and have no 50 chance at all to recombine. The hydrogen produced by anodic reduction of the wires is also liberated at the cathode. In the alternating current apparatus, on the other hand, the hydrogen and oxygen produced by electrolysis and the hydrogen produced by anodic reduction are 55 liberated at the same electrodes, since in each cell the wires function alternately as cathode and anode, and the gases have an opportunity to recombine. The formation of water in this 60 way results in some reduction in gassing even if low frequency 60 cycle alternating current is used. The effect is increased with an increase in the frequency and it is advantageous, therefore, to use a fairly high frequency. Frequencies on the order of 1000 to 5000 cycles per second 65 may be used with good results.

The reduction in the amount of gassing has the special advantage that the tendency to 70 polarization of the wires is reduced and the reduction of the wires is correspondingly accelerated.

At the same time that the switch S1 is closed to start the anodic reduction process the switch 75 S2 may be closed also, to start the motor 98.

The shaft 94 accordingly starts to rotate to wind the wires 81-84 up on the spools 89-92 and draw the wires through the electrolytic cell system. The speed at which the wires are drawn through the cells depends on the setting of the variable speed mechanism 99 through the medium of which the motor 98 rotates the shaft 94.

The operator will be provided with instructions which will enable her to produce tapered wires or conductors having the length and taper required. These instructions may, for example, specify a wire having a definite number of sections, the length and pulling speed of which are designated. The length of the sections may be given in terms of rotations of shaft 94 while the pulling speeds may be given as different settings of the variable speed mechanism. These settings are calculated in advance in accordance with the taper required.

Before starting the operation, therefore, the operator will adjust the knob 100 of the variable speed mechanism to the correct setting for the first section. Then, as the wires are pulled through, the operator counts the rotations of shaft 94 to keep track of the sections and as each section emerges from the electrolytic cell system she will adjust the knob 100 to the setting which is specified for the next section. A rotation counter may be used in connection with shaft 94, if desired, and will be of assistance to the operator.

When the end sections have been pulled through, and a few feet of wire in addition, the operator will stop the operation by opening the switches S1 and S2. The switch S3 may be left closed assuming that more tapered wires are to be made. The wires on the take-up spools are now cut off one at a time where they emerge from the electrolytic cell system, the winding of these wires on the spools is completed by hand, and the spools are removed from the shaft 94. Four tapered wires have now been completed.

To make four more tapered wires, the operator will place four empty take-up spools on shaft 94, and reset the variable speed mechanism. The wires 81-84 are then cut off just to the left of the point where they enter the electrolytic cell system and the sections of wire in the electrolytic cell system are lifted out and discarded. The ends of the wires on the spools 85-88 are then passed beneath the guide rods and are attached to the take-up spools as before. These matters having been attended to and the wires having been adjusted in the grooves of the guide rods and in the slots of the cell walls, the switches S1 and S2 may be closed again, whereupon the described tapering operations are repeated.

The apparatus may also be used for manufacturing very fine wire of uniform diameter, starting with a wire having a diameter of 4 or 5 mils such as can conveniently be produced by drawing and reducing it to the desired smaller diameter by pulling it through the electrolytic cell system. The pulling speed is determined in accordance with the reduction required and is maintained constant throughout the operation.

The invention having been described, that which is believed to be new and for which the protection of Letters Patent is desired will be pointed out in the appended claims.

I claim:

1. Apparatus for processing wire by anodic reduction, comprising two groups of electrolytic

- 75 cells, said cells being arranged in a row with the cells of one group alternating with the cells of the other group, means for drawing a wire through said cells, two independent circulating systems for circulating electrolyte through said two groups of cells, respectively, said systems including parts made of insulating material for insulating the electrolyte in one system from the electrolyte in the other system, an electrode in each cell, a source of alternating current, and conductors connecting one terminal of said source to the electrodes in one group of cells and the other terminal of said source to the electrodes in the other group of cells.
- 15 2. An electrolytic cell system for the anodic reduction of wires, comprising a plurality of electrolytic cells spaced apart in a row, a header extending parallel to said row on one side thereof and communicating with the odd numbered cells, a header extending parallel to said row on the opposite side thereof and communicating with the even numbered cells, two electrolyte storage reservoirs, discharge outlets for the odd numbered cells emptying into the first of said reservoirs, discharge outlets for the even numbered cells emptying into the second of said reservoirs, two pumps for transferring electrolyte from the first and second reservoirs to the first and second headers, respectively, means for drawing wires through said cells, a source of alternating current, electrodes in the odd numbered cells connected in parallel to one terminal of said source, and electrodes in the even numbered cells connected in parallel to the other terminal of said source.
- 20 3. An electrolytic cell system for the anodic reduction of wires, comprising a plurality of electrolytic cells spaced apart in a row, a header extending parallel to said row on one side thereof and communicating with the odd numbered cells, a header extending parallel to said row on the opposite side thereof and communicating with the even numbered cells, discharge outlets for the odd numbered cells, discharge outlets for the even numbered cells, the discharge outlet for each cell being located at the end opposite the header with which the cell communicates, a circulating system for collecting electrolyte from the discharge outlets for the odd numbered cells and transferring it to said first header, a circulating system for collecting electrolyte from the discharge outlets for the even numbered cells and transferring it to said second header, means for drawing wires through said cells, a source of alternating current, cathodes in the odd numbered cells connected in parallel to one terminal of said source, cathodes in the even numbered cells connected in parallel to the other terminal of said source, and parts in said
- 25 40 45 50 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935 940 945 950 955 960 965 970 975 980 985 990 995 1000
